UNITED STATES PATENT OFFICE.

GEORGE A. BERTSCH, OF PROVIDENCE, RHODE ISLAND.

ROTARY REVERSIBLE MOTOR.

1,262,164.

Specification of Letters Patent.

Patented Apr. 9, 1918.

Application filed October 7, 1916. Serial No. 124,320.

To all whom it may concern:

Be it known that I, GEORGE A. BERTSCH, a citizen of the United States, residing at Providence, in the county of Providence and

5 State of Rhode Island, have invented certain new and useful Improvements in Rotary Reversible Motors; and I do hereby declare the following to be a full, clear, and exact description of the invention, such as 10 will enable others skilled in the art to which it appertains to make and use the same.

This invention relates to new and useful improvements in rotary reversible motors and the principal object of the invention is 15 to provide a motor from which the maximum power is obtained from a minimum consumption of fuel.

A further object of the invention is to provide a device in which the flow of the 20 expending gas may be directed against the piston heads of the rotor in such a manner as to drive the same in a forward or reverse direction.

The invention has for another object to 25 provide a rotor arranged to operate within the motor casing or stator which is provided with a pair of laterally extending annular ribs which project from opposite sides of the rotor which ribs are cutaway for portions of their length to allow for the turning of the piston heads against which the gases are directed and impinge.

Still another object of the invention is to provide a means for turning the piston heads 35 so they extend in a plane with the rib at a time when they are passing between the portions of the directing vane which is rockably mounted so as to change the direction of flow of the gas through the device.

40 A still further object of the invention is to provide a novel means for holding the rockable vane in its various positions.

A still further object of the invention resides in the provision of a novel means for 45 mounting the pistons in the rotors and to balance the same so as to prevent endwise movement and yet allow each of the pistons sufficient resiliency to give when pressure is applied to their outer ends thereby avoiding 50 danger of injury thereto.

With these and other objects in view the invention consists in the novel combination

and arrangement of parts which will be fully set forth in the following specification and accompanying drawings, in which:—

55

Figure 1 is an end elevation of the motor illustrating the drive shaft and a portion of the exhaust manifold in section.

Fig. 2 is a vertical longitudinal sectional view of the motor showing the same on an 60 enlarged scale to more clearly illustrate the details of construction.

Fig. 3 is a vertical sectional view taken on line 4—4 of Fig. 2 and showing the device on a reduced scale.

65

Fig. 4 is a vertical sectional view on line 5—5 of Fig. 2.

Fig. 5 is an enlarged detail longitudinal sectional view through a fragment of the rotor and illustrating the detail construction 70 of the piston.

Fig. 6 is an enlarged detail view partly in section of the piston operating mechanism.

Fig. 7 is a detail view of one of the elements of the piston.

75

Referring more particularly to the drawings the motor is generically indicated by the numeral 1. The fuel or operating gas of the motor is fed thereto through a manifold 3, having a reduced portion 26 and a 80 branch or elbow pipe 27 which conducts the gases to the operating chambers within the motor where they expand against the heads of the rotor and operate the motor, from which the power is transmitted through the 85 drive shaft 4.

The stator of the motor comprises two separate body sections designated respectively by the numerals 43 and 44. The body 43 includes a hub 45 having extending radially therefrom an annular wall 46 which is positioned near the inner end but spaced therefrom for a short distance. The outer edge of the wall is formed with an annularly extending enlarged portion 47 having 90 formed therein an annular passage 48 forming the inlet passage through which the expanding gases enter the device. An annular groove 49 is formed in the inner face of the enlargement 47 and forms the chamber in 100 which the pistons of the rotor operate. A suitable inwardly extending flange 49' is formed at the extreme periphery of the enlargement 47 and coöperates with a similar

flange on the opposite section 44 in housing the rotor. A suitable annular groove 50 is formed in the inner face of the flange 46 and is adapted to receive suitable packing rings to prevent the escape of fluid. The hub 45 is provided with a longitudinal bore in which a suitable bearing bushing 51 is positioned in which the shaft 4 is rotatably mounted.

10 The stator section 44 comprises a hub 52 formed with an annular flange 53 at its inner end which is formed at its periphery with an enlargement 54 having an annular passage 55 therein which corresponds to the 15 passage 48 and forms a fluid conductor through which the expanding gases pass. A suitable annular groove 56 is formed in the inner face of the enlargement 55 to accommodate the heads and web of the rotor 20 and this groove is similar to the groove 48 previously referred to. A suitable inwardly extending flange 57 is formed at the periphery of the enlargement 54 and co-operates with the flange 49 in housing the rotor. The 25 point where the flange 53 and enlargement 54 join is rabbeted as at 58 to form an annular chamber for the reception of a suitable packing which chamber corresponds to the groove 50 hereinbefore described. In 30 order to conduct the inflowing gases to the proper point to impinge against the heads of the rotor the section 43 of the stator is formed with an arcuate passage 59 which passage is arranged in the enlargement 47 and extends in opposite directions from the 35 inlet port 60 and communicates at both ends with the passage 48. A similar passage 61 is formed in the enlargement 54 of the section 44 and communicates with the elbow 27 through a port 62. It will thus be seen 40 that the gases passing in through the manifold 3 will be directed against both rotors of the device. Each of the stator sections 43 and 44 is provided with a plurality 45 of longitudinally extending apertures 63 through which the connecting bolts 64 extend which bolts hold the members in proper position.

Formed at the outlet side of the section 43 50 of the stator is an outlet port 65 which has the branch pipe or elbow 66 of the outlet or exhaust manifold 10 in communication therewith as clearly shown in Fig. 2. A suitable opening 67 is formed in the enlarged portion 47 and receives the hub portion 55 of the reversing valve or vane which will be more fully hereinafter described. As illustrated in the drawings a transverse bore 68 extends through the enlarged portion 47 60 and communicates at its inner end with the interior of the stator or chamber in which the rotor is mounted. This bore 68 establishes communication between the passage 48 and the passage 49 as illustrated in Figs. 65 2 and 3 and is arranged in alinement with

the outlet port 65. A similar transverse bore 69 is formed in the section 44 of the stator and establishes communication between the passage 55 and the passage 56 and is also arranged in alinement with the outlet port 70 which is connected with the elbow 71 of the manifold designated generally by the numeral 10.

In order to control the direction of the flow of gas through the device, suitable valves are provided which comprise a pair of disks 72 which are rotatably mounted in the openings 67 and 69 respectively. These disks are provided with the stems 73 which extend through suitable cover plates 74 which are bolted or otherwise attached as at 75 to the sides of the stator and attached to the outer ends of the stems 73 are suitable operating levers 76 by means of which the positions of the valve are changed when it is desired to reverse the rotation of the device. One of the levers 76 is formed with a plurality of notches 77 which are adapted to receive a stop lug 78 which is formed centrally of a resilient plate 79 mounted between suitable studs 80 on the plates 74. Suitable stop lugs 81 are formed on each plate 74 and are adapted to limit the throw of the levers 76. Formed on the inner face of each of the disks 72 are a pair of spaced vanes 82 and 83. The vane 82 is adapted to fill the space between the rib of the rotor and the wall separating the passages 48 and 49 while the vane 83 extends between the rib on the rotor and the outer walls of the passage 49 and as shown in Fig. 4, these vanes are provided along their adjacent edges with substantially V-shaped faces 84 which faces are so shaped that they will allow the ribs on the rotor to easily pass between the vanes 82 and 83 and yet will effectively prevent the escape of expanding gases between the vanes and ribs.

Passing now to the description of the rotor, reference will be had particularly to Figs. 3 and 5. This rotor comprises a hub 85 provided with an outwardly extending annular wall 86 formed at its periphery with the angularly extending wall 87. This wall 87 terminates at its extreme outer end in a vertical wall 88 which in turn is formed at its periphery with a wall 89 which extends in spaced parallel relation with the wall 87. A vertically extending circular wall 90 joins the edge of the wall 89 opposite the wall 88 and is formed integrally with the hub adjacent the end opposite that adjacent which the wall 86 is formed. It will thus be seen that a cooling space 91 is formed interiorly of the rotor by means of which a cooling fluid is admitted to the device to keep the temperature of the motor from rising to such a degree as to render the device inoperative. Formed intermediate the edges of the wall 88 and extend-

ing outwardly from said wall at right angles with relation thereto is an annular flange or rib 92 the side faces of which incline toward the outer edge of said rib and 5 a similar rib 93 is formed on the wall 90 in the same plane with the rib 92. These ribs are adapted to travel in the passages 49 and 56 respectively and each of said ribs is formed at spaced intervals throughout its 10 length with the openings 94 in which the piston heads are operable. Formed at spaced intervals within the rotor are suitable pockets 95 for the accommodation of the pistons and the operating mechanism 15 for said pistons. In order to insure the proper circulation of the cooling fluid through the device, the inner terminals of the passages 91 communicate with a bore 96 in the shaft 4 and a pipe 97 which is of 20 considerably less diameter than the bore 96 extends axially through said bore and communicates at its inner end with a reduced bore 98 which in turn is in communication with the radial passages 99, the outer 25 ends of which are in communication with the passages 91. It will thus be seen that the cool water flowing into the pipe 97 will be conveyed through the bore 98 and radial passages 99 into the passages 91 where it 30 will circulate against the wall of the passages 91 and after becoming heated pass into the bore 96 where it is conveyed to a suitable cooling coil or radiator designated in the diagram by the numeral 100. A 35 suitable cover plate 101 is provided for the side of the rotor on which the wall 88 is formed so as to complete the house thereby providing the necessary lubricating space not subject to the pressure of the gases for 40 the operation of the mechanism within the rotor. The wall 88 is formed at spaced intervals with openings 102 which align with openings 103 formed in the wall 90 and these openings are arranged to communicate 45 with the pockets 95 hereinbefore described. The openings 102 and 103 above referred to are adapted to accommodate the pistons which will be more fully hereinafter described. 50 The pistons above mentioned are best illustrated in Fig. 6 and each of said pistons comprises an internally threaded sleeve 104 formed at opposite ends with reduced cylindrical trunnions 105 which are rotatably 55 mounted in the bushings 106 which in turn are fitted in the openings 102 and 103. Threaded into the sleeve 104 are suitable stems 106' having formed at their outer ends the bodies or disks 107 which in turn are 60 formed with transversely extending arcuate heads 108. These heads 108 are curved to conform to the curvature of the ribs 92 and 93 and are of a width equal to the distance between the end walls of the openings 94. 65 In order to hold the pistons in place and

against accidental movement, suitable tapered pins 109 are driven through tapered openings drilled in the sleeve 104 and the stems 106 and thus any accidental movement of the heads is eliminated. In 70 order to prevent the gases under pressure from entering the interior of the rotor partly cupped disks of spring steel are positioned between the pistons 107 and the sleeve 105. Clearance shown between disks 75 107 and bushings 106 are greatly exaggerated in order to show that disks 110 are made of suitable springy material. The clearance between the disks and bushings 107 is limited to .002" or .003" of one inch. 80

From the foregoing description it will be seen that the rotor is formed with a central chamber 112 in which the piston actuating mechanism is mounted.

The piston actuating mechanism above 85 mentioned is best illustrated in Figs. 3 and 5 and comprises a cam 113 which is mounted on the inner end of the bushing 51. This cam is circular in cross section and is formed with a cam groove 114 in which the piston actuating rollers run. The wall 86 of the rotor has bolted or otherwise attached thereto suitable guide plates 115 which are provided with the outwardly extending guide flanges 116 in which the sliding rack 95 bars are slidably mounted. The sliding rack bars above referred to comprise the bodies 117 formed with the longitudinally extending stems 118 which are provided adjacent their outer ends with a plurality of 100 rack teeth 119. These teeth are adapted to mesh with the teeth 120 formed on the exterior of the sleeve 104 and it will thus be seen that as the slide 17 moves inwardly or outwardly, the sleeve 104 will be rotated. 105 In order that the sleeve may be rotated, the body 117 has extending outwardly therefrom a stud 121 on which a roller 122 is mounted and as shown in Figs. 3 and 5, the rollers 122 project into the cam groove 114 110 and when each piston head is downwardly, it will be seen that the cam will operate to cause the piston head which is in the lowermost position to turn into the position illustrated in Fig. 4 so as to pass between the 115 vanes 82 and 83.

The gases used to operate the engine are delivered in any suitable manner to the manifold 3 from which it will enter the motor by passing through the port 60 and out 120 through the passage 59 into the annular passage 48 from whence the gas will pass through the opening 68 and then into the passage 49 between the annular ribs 92 and 93 and the walls between the passages 48 125 and 49 and 55 and 61 and in passing into the passages 49 and 61 the gas will impinge against the piston head which extends transversely of the passages 49 and 56 thereby driving the rotor in the direction of the flow 130

of the gas through the passages previously referred to. After the gas has made a complete revolution, it will be seen that the same will pass out through the ports 65 and 70 and into the exhaust manifold 10 where it enters the atmosphere. Should it be desired to reverse the operation of the motor it will be seen that the reversing lever 123 which is pivoted at 124 is shifted thereby 10 by imparting motion through the link 125 to the levers 76 which movement will cause the stems 73 to partially rotate thus moving the vanes to the desired position. Upon the movement of the rotor within the stator, 15 it will be seen that as the heads move toward the vanes 82 and 83, the cam will move the slide inwardly thus causing the sleeve to rotate and move the piston heads so that they align with the ribs and after the same 20 have passed between the vanes the cam again turns the heads so as to extend transversely of the passages and in such a manner that the gases will again impinge against the active faces of the heads and thereby 25 keep the rotor in motion.

While in the foregoing there has been shown and described the preferred embodiment of this invention, it is to be understood that such changes may be made in the 30 combination and arrangement of parts as will fall within the spirit and scope of the invention as claimed.

What is claimed is:—

1. In a reversible rotary motor, a stator 35 having a pair of annular passages arranged therein, a rotor within the stator, said rotor carrying a pair of oppositely extending annular ribs arranged centrally of the annular passages in the stator, heads rotatably 40 mounted in the rotor, the stator being provided with a transverse bore near its lower end and having an inlet passage leading to the transverse bore, said inlet passage communicating with the annular passage 45 through the transverse bore, the stator having an outlet passage communicating with the transverse passage, and vanes operable in the bore to direct the passage of inflowing gases against the heads of the rotor and 50 directing the outflowing gases into the exhaust manifold.

2. A reversible rotary motor including a stator having a pair of annular passages arranged therein, a rotor operable within the 55 stator, flanges on the rotor extending into the annular passages, the stator being provided with inlet ports and having a transverse bore near its under side through which the inlet ports communicate with the annular passages, said stator also having outlet 60 ports communicating with the annular passages, heads extending transversely of the annular passages, said heads being adapted to be turned longitudinally to extend in a 65 plane with the flanges and vanes for direct-

ing the flow of the gases from the inlet ports into the annular passages and thence to the outlet ports.

3. In a reversible rotary motor, a stator having a pair of annular passages arranged therein, a rotor within the stator, ribs on the rotor and arranged centrally of the annular passages in the stator, transverse bores extending through the rotor at spaced intervals, pistons within the transverse bores, 75 heads on the pistons conforming to the shape of the ribs and adapted when turned in one position to extend transversely of the ribs and when turned into another position to extend longitudinally of the ribs, a stationary 80 cam carried by the stator, carriages slideable within the rotor, rack bars carried by the carriages, segments carried by the pistons and meshing with the rack bars, and cam rollers on the carriages to cause the said 85 carriages to reciprocate according to the direction of the cam.

4. In a reversible rotary motor, a stator having a pair of annular passages arranged therein, said stator also having inlet ports 90 formed laterally of the annular passages and being provided with a transverse bore at its lower end establishing communication between the annular passages and the inlet ports, the stator also having an outlet port 95 communicating with the transverse bore, and vanes rockably mounted in the annular passages for directing the flow of gases through the annular passages.

5. In a reversible rotary motor, a stator 100 having a pair of annular passages arranged therein, a rotor within the stator, said rotor carrying a pair of oppositely extending annular ribs arranged centrally of the annular passages in the stator, heads rotatably 105 mounted in the rotor, the stator being provided with a transverse bore near its lower end and having an inlet passage leading into the transverse bore, said inlet passage communicating with the annular passage 110 through the transverse bore, the stator having an outlet passage communicating with the transverse passage, and means for directing the inflowing gases against said heads. 115

6. In a reversible rotary motor, a stator having an annular passage, a rotor within the stator, an annular rib formed upon the rotor and arranged centrally of said annular passage, pistons having heads carried by 120 said rib, and means for turning said pistons transversely to or in alignment with said rib, including a cam carried by said stator, carriages slideably supported by said rotor and slideable by engagement with said 125 cam, and means connecting said carriages and said pistons for intermittently rotating the piston upon sliding movement of the carriages.

7. In a reversible rotary motor, a stator 130

having an annular passage, a rotor within the stator, an annular rib formed upon the rotor and arranged centrally of said annular passage, pistons having heads carried by said rib, and means for turning said pistons transversely to or in alinement with said rib, including a channel cam carried by said stator, carriages slidably supported by said rotor, rollers carried by said carriages and riding in the channel of said cam for reciprocating said carriages during the rotation of said rotor, means connecting said carriages and said pistons for intermittently rotating the pistons upon reciprocatory movement of the carriages. 35

8. In a reversible rotary motor, a stator having an annular passage, a rotor within the stator, an annular rib formed upon the rotor and arranged centrally of said annular passage, pistons having heads carried by said rib, and means for turning said pistons

transversely to or in alinement with said rib, including a channel cam carried by said stator, carriages slidably supported by said rotor, rollers carried by said carriages and riding in the channel of said cam for reciprocating said carriages during the rotation of said rotor, means connecting said carriages and said pistons for intermittently rotating the pistons upon reciprocatory movement of the carriages, and vanes operable to direct the passage of inflowing gases against the heads of said pistons and directing the outflowing gases into the exhaust manifold. 35

In testimony whereof I affix my signature in presence of two witnesses.

GEORGE A. BERTSCH.
